UNITED STATES PATENT OFFICE.

GEORGE A. FULLERTON, OF BOSTON, MASSACHUSETTS.

MACHINE FOR MAKING COMPOUND FABRICS.

SPECIFICATION forming part of Letters Patent No. 398,320, dated February 19, 1889.

Application filed April 8, 1887. Serial No. 234,102. (No model.)

To all whom it may concern:

Be it known that I, GEORGE A. FULLERTON, of Boston, in the county of Suffolk and State of Massachusetts, have invented a new and useful Machine for Making Compound Fabrics, of which the following is a specification, reference being had to the accompanying drawing, forming a part hereof.

My invention consists in a machine for making compound fabrics, and relates especially to the fabric patented by my Letters Patent, No. 308,603, dated December 2, 1884, though it may be practiced advantageously in the manufacture of other compound fabrics.

15 In the drawing, which is a view, partly in section, of my new machine, (with one of its side frames removed for greater clearness,) and which shows coils of sheet material, hanging rolls, brakes, and the compound fabric reeled, A is a glue-distributing device made up of a well, a, a distributer, a', and a press-roll, a². B is the powder-distributing device, (patented by J. W. Baldwin by Letters Patent No. 351,483, dated October 26, 1886,) and 20 is made up of a reservoir, b, a measuring-roll, b', a striker, b², and an adjustable distributing-brush, b³ b⁴, and D is a compressing device made up of rolls d d', &c. All these parts are mounted in frame F, the rolls being properly 25 journaled therein, as will be readily understood from the drawing without particular description, the roll d being rotated by the meshing of gear 1 with pinion 2, and rolls a², b³, d', d², and d³ being adjusted by means of set-screws f in a way too well known to require 30 description.

As it is necessary that the glue or the like should be kept in an adhesive or sticky condition until the compound fabric is made, I 35 make the roll d with a hollow shaft for the introduction of steam in a way too well known to require description.

The scrapers g are journaled in frame F, and their edges are brought into harder or 40 lighter contact with the rolls a², d, d', and d² by adjustment of their weights g', whereby the rolls are kept clean and free from glue or the like.

One of the sheets, X, of which the compound fabric Z is composed is placed at a con-

venient distance from the machine, and one of its ends is carried over a roll, x, conveniently hung from the ceiling under a brake, x', and over another hanging roll x, past brush x² and rolls x³, between distributer a', 55 which rotates in well a, and its press-roll a², by means of which the glue is laid evenly on the sheet X, to the compressing-rolls d d', where another constituent sheet, Y, of the compound fabric meets it, one end of sheet Y being carried past rolls y and a brake, y', as will be plain from the drawing. By carrying the sheets over and past the rolls and brakes x x' and y y' the sheets are freed from wrinkles and made smooth for the reception of the glue 60 treated with powdered chrome alum, and the action of brush x² cleans the sheet X before it reaches the glue-distributing device A. The sheet X, on its way from glue-distributing device A to compressing device D, passes with its 65 glue side uppermost under powder-distributer B, by means of which I dust the glue-treated surface of sheet X with powdered chrome alum, with which I supply reservoir b, and by bringing sheets X and Y together in the compressing device I am able to produce a greatly 70 improved variety of my said patented fabric, the rolls d d' d d' d² d³ compressing the sheets X and Y together and causing them to unite with great firmness, and the chrome alum 75 mixing with the glue, because of its being powdered, so as to produce a much better product than is obtained when the glue is treated with chrome alum in other ways. After the compound fabric leaves the compressing device D it is ready to be reeled and to be carried to the drying-room. It is plain that either or both sheets X Y may be sheets of 80 simple or compound fabric.

I am aware of Patents No. 238,991, Toye, 90 March 15, 1881; No. 97,221, Ormsby, November 23, 1869; No. 247,582, Sargeant, September 27, 1881; No. 168,186, Russell, September 28, 1875; No. 175,774, Siehmon and Rost, April 4, 1876; No. 34,021, Wilson, December 24, 1881, 95 and No. 237,055, January 25, 1881, and disclaim all that is shown in them.

What I claim is—

The herein-described combination of glue-distributing device A, powder-distributing 100

device B, and compressing device D, with two sets of guides, one set guiding material to the glue-distributing device and another set guiding material to the compressing device, the powder device being mounted between the glue-distributing device and the compressing device, and that set of guides which directs the material to the compressing device being

mounted to direct the fabric to meet the powdered surface of the other sheet, substantially as and for the purpose set forth.

GEO. A. FULLERTON.
